2 098 958	12/1982	United Kingdom .

[75] Inventors: **Stephen J. Mohary**, Pennington, N.J.;
Craig M. Saunders, Rocky River;
Jesse P. Carlson, Cleveland, both of
Ohio

[73] Assignee: **Johnson & Johnson Consumer Products, Inc.**, Skillman, N.J.

[**] Term: **14 Years**

[21] Appl. No.: **29/076,362**[22] Filed: **Sep. 9, 1997**

[51] **LOC (6) Cl. 09-07**
[52] **U.S. Cl. D9/449**

[57] **CLAIM**

The ornamental design for an angled cap, as shown and described.

DESCRIPTION

FIG. 1 is a perspective view of the cap of our new design; FIG. 2 is a left side elevational view thereof; FIG. 3 is a right side elevational view thereof; FIG. 4 is a top plan view thereof; and, FIG. 5 is a front elevational view thereof; the rear elevation being a mirror image. The bottom and interior of the closure form no part of the claimed design.
